[57] CLAIM

The ornamental design for a packaging tray for containing and dispensing razor blade units, as shown and described.

DESCRIPTION

FIG. 1 is a perspective view from above of the front, top, and one side of a packaging tray for containing and dispensing razor blade units showing my new design; FIG. 2 is a perspective view from below of the rear, bottom, and the side opposite that seen in FIG. 1, thereof;

FIG. 3 is a front elevational view thereof;

FIG. 4 is a rear elevational view thereof;

FIG. 5 is a side elevational view showing the side seen in FIG. 1, thereof, and

FIG. 6 is a bottom plan view thereof.

FIG. 1.

FIG. 2.

FIG. 3.

FIG. 4.

FIG. 5.

FIG. 6.
